GOGGLES

Filed June 28, 1929

INVENTOR.
HERMAN NEUWIRTH

Louis Barnett
ATTORNEY.

UNITED STATES PATENT OFFICE

HERMAN NEUWIRTH, OF BROOKLYN, NEW YORK

GOOGLES

Application filed June 28, 1929. Serial No. 374,348.

This invention relates to goggles, such as worn by aviators, automobilists, motor boat pilots and mechanics. More particularly the invention is directed to a goggle of novel construction having an improved type of cushioning means carried by the goggle frame.

Among the objects of the invention is to generally improve the construction of goggles of the character described and to provide a 10 goggle comprising few and simple parts, which shall be easily assembled, relatively inexpensive to manufacture, forms a neat appearing convenient accessory, which shall be comfortable to wear, and practical and efficient to a high degree in use.

Other objects of this invention will in part be obvious and in part hereinafter pointed out.

The invention accordingly consists in the 20 features of construction, combinations of elements and arrangement of parts which will be exemplified in the constructions hereinafter described and of which the scope of application will be indicated in the following claims.

25 In the accompanying drawing, in which is shown various possible illustrative embodiments of this invention,

Fig. 1 is an elevational view of goggle constructed to embody the invention as seen from 30 the side adapted to abut the wearer's face.

Fig. 2 is an enlarged cross-sectional view taken on lines 2—2 in Fig. 1.

Fig. 3 is a fragmentary bottom plane view as seen from lines 3—3 in Fig. 1.

35 Fig. 4 is an elevational view of the improved cushion removed from the goggle frame.

Fig. 5 is an elevational view similar to Fig. 1 showing the feature of the invention 40 applied to a different type of goggle.

Fig. 6 is an elevational view similar to Fig. 4 showing modified form of the improved cushion embodying the invention, and

45 Fig. 7 is an enlarged cross sectional view taken on lines 7—7 in Fig. 6.

Referring in detail to the drawing, and particularly to Figs. 1 to 4, inclusive, 10 denotes an improved goggle construction embodying the invention. Said goggles 10 include a frame comprising eye pieces 11 and 12

which preferably are interconnected by a 55 slideable adjustable nose bridge 13 through suitable swivelling joints 14. Each piece may comprise a metallic strip bent to form an oval ring having the ends of the strip coupled together by a releasable joint of suitable construction such as an I-bolt 15 positioned on the outer end of the ring, the swivelling joint 14 being secured to the inner end of said ring as shown in Figs. 1 and 3.

60 The I-bolts 15 form convenient anchorage for the hook ends 16 of a head strap 17 of any well understood construction.

65 The eye pieces each are provided with an inturned edge flange 11^a and lugs 18 projecting from the inner surface thereof, said lugs 18 being spaced from the flange 11^a to provide means for tightly engaging and gripping the rim of a lens 19 fitted and secured into the eye piece. The eye piece may also have a rim 70 ledge 11^b positioned to extend from the side of the ring opposite the flange 11^a, the latter forming a base on which a suitable cushion 20 is mounted. For firmly attaching the cushion 20 to the eye piece an integral lip extension 75 20^a is provided on the cushion which is adapted to receive a suitable fastening means as for example, stitches 21^a.

75 The latter pass through spaced perforation 11^c provided in the ledge 11^b as shown in Fig. 3. The eye pieces 11 and 12 are curved or bowed as seen from Fig. 3 to conform to the shape of the wearer's head about the eye region and the lower or under portion of the eye piece ring is preferably extended along a 85 rim portion 11^d thereof to more closely conform the wearer's features under the eyes and adjacent the nose.

85 For ventilation the interior side of the goggle when worn, suitable inlet and outlet air 90 passage means 21 may be provided in each of the eye piece structures as shown in Figs. 1, 2 and 3.

95 The cushions may be made of any suitable material, such as sponge rubber which has been found satisfactory. Preferably the cushions are molded in circular shape having a substantially uniform cross-section with the lip extension 20^a projection completely around one side of the cushion, as shown in 100

dotted lines in Fig. 4. Projecting from the side of the cushion opposite the lip extension 20^a there is provided an integrally formed fin 20^b which extends only partially the circumferential length of the cushion.

The cushions are attached to the eye pieces of the frame with the fins positioned substantially as shown in Figs. 1 and 3 for the purpose as will hereinafter more fully appear.

The practical application of the invention will now be readily understood. The parts of the goggles 10 are assembled in the relative position as shown in the drawing.

15 The lens 19 may be readily removed or replaced by simply releasing and opening the eye piece joint at the I-bolt 15 to disengage the rim of the lens from its seated position between the flange 11^a and the lugs 18.

20 The extended lower rim portion 11^a of the eye piece ring projects the adjoining portion of the cushion into the usual hollow at the side of the wearer's nose under the eye.

25 The fin 20^b which is very flexible and extends beyond the outer surface of the projected portion of the cushion forms an abutment barrier that is self-adjusting for contacting the wearer's face so that on movements of the wearer's head or displacement 30 of the goggles due to high wind pressure from the side, the sealed joint formed by contact of the cushion with the wearer's face is thus left intact, since the fin acts as a self-closing and self-conforming means for preventing the wind stream from accidentally entering the goggles between the cushion of the wearer's face.

In the Fig. 5 a modified construction of goggle 110 is shown embodying the invention.

40 Here the frame is formed with a covering of rubber so that no metallic parts are exposed. The cushion 120 about the eye pieces is provided with the fins 120^b in the same manner and for the same purpose described 45 above for the goggles 10.

45 A modified construction of fin embodying the invention is shown in Figs. 6 and 7. The fin 220^b on the cushion 220 is made with a depression or groove 220^c extending lengthwise the fin. By slightly moistening the surface of the groove 220^c it may be made to serve as a suction cup when flattened against the wearer's face in the well understood manner. This suction attachment will serve to retain the fin from being accidentally separated from its contacting position.

50 The goggle constructions described above provide an unusual practical and efficient means for guarding the wearer's eye against injury yet can be worn continuously without discomfort.

55 It will thus be seen that there is provided devices in which the several objects of this invention are achieved and which are well

adapted to meet the conditions of practical use.

As various possible embodiments might be made of the above invention, and as various changes might be made in the embodiments above set forth, it is to be understood that all matters herein set forth or shown in the accompanying drawing are to be interpreted as illustrative and not in a limiting sense.

Having thus described my invention, I 75 claim as new and desire to secure by Letters Patent:

1. In a goggle of the character described, an annular cushioning member having a flexible fin projecting from the face contacting surface thereof adapted to contact with and shaped to conform to a depressed portion of the wearer's face.

2. An annular cushioning member of substantial uniform cross-section adapted to be 85 mounted on a goggle frame having a projecting flexible fin structure extending partially the length of the circumferential surface thereof, and suction means formed in the fin structure for retaining contact with the 90 wearer's face.

3. In a goggle of the character described, a frame having eye pieces each provided with means for retaining a lens, a cushioning ring mounted on each piece, each frame eye piece having a projecting portion for extending a portion of the ring to conform to the contour of the wearer's face, and a flexible fin extending from the face contacting surface 95 of the extended portion of the ring.

In testimony whereof I affix my signature.

HERMAN NEUWIRTH.
